UNITED STATES PATENT OFFICE.

JOSEPH S. KNOWLES, OF ATLANTA, ILLINOIS.

FIRE-ESCAPE.

1,182,492.

Specification of Letters Patent.

Patented May 9, 1916.

Application filed January 3, 1916. Serial No. 69,856.

To all whom it may concern:

Be it known that I, JOSEPH S. KNOWLES, a citizen of the United States of America, and a resident of Atlanta, county of Logan, State 5 of Illinois, have invented certain new and useful Improvements in Fire-Escapes, of which the following is a full and clear specification.

This invention relates to that type of fire- 10 escape employing a depending ladder which is adapted to be moved along the face of a building to rescue persons from the windows of the upper floors of the building, and the invention consists of certain novel features 15 of construction hereinafter described and claimed.

In the drawings—Figure 1 is a side elevation of part of a building showing my apparatus applied thereto; Fig. 2 is a detail perspective view of the hammock for lowering persons to the ground; Fig. 3 a detail front elevation of a part of the ladder showing a detachable platform connected thereto; Figs. 4, 5 and 6 detail views of the mechanism 25 for raising and lowering the hammock; and Figs. 7, 8, 9, 10, 11 and 12 details of other parts of the device hereinafter described.

Referring to the drawings annexed by reference characters, 1 designates a horizontal 30 track which is fastened to the face of the building along the top thereof by means of suitable brackets 2, which are held against the face of the building by long bolts 3 passing through the track-rail and the bracket 35 and also through the wall of the building, the lower end of each bracket being provided with an integral spike 4 adapted for insertion between the bricks of the building.

Adapted to run along the track is a 40 hanger appliance consisting essentially of a pair of hanger irons or rods 5 carrying rollers 6 at the upper ends and being attached at their lower ends to a horizontal bar 7. The hangers are attached to the bar 7 by 45 having their lower ends extended through holes therein, the lower extremities of the hangers each being provided with a nut 8 which affords an anti-friction roller bearing cup 9 in such position that the balls of the 50 cup support the bar 7. This bar 7 serves to rigidly connect the hangers, and a swivel connection between the board and each hanger permits each hanger to have a slight independent rotative action, to thereby enable it to swivel sufficiently to insure the 55 wheels 6 running true on the track.

Pivotedly hung from bar 7 is a ladder composed of sections 10 which are detachably connected together end to end by suitable hinges 11. By hinging the sections of 60 the ladder together, the sections may be swung outwardly away from the building far enough to permit them to pass by obstructions such as balconies, sheds, etc. This hinge construction will be especially advan- 65 tageous for the lower section of the ladder, as that section should be so hung to the upper part of the ladder that it may be readily swung outwardly and upwardly so as to pass over fences, sheds, etc. By detachably 70 connecting the sections of the ladder, it will be seen that the ladder may be readily made shorter or longer as the exigencies of the particular case may require.

The raising and lowering appliance consists of a rather heavy shaft 12 which is adapted to be suspended on the front side of the ladder at any point throughout the length thereof by means of a pair of hooks 13, whose upper ends are adapted to be hung 75 upon one of the rungs of the ladder. Suitable blocks 14 are attached to the shaft 12 at their lower ends to support it slightly away from the face of the ladder. Rotatively mounted on the shaft 12 is a drum 15 which 80 is free to rotate in one direction, but is prevented from rotating in the opposite direction by means of a pair of spring pawls 16 mounted on the non-rotative shaft 12 in such position as to normally press into engagement 85 with ratchet-like notches formed in the ends of the drum sleeve 15.

A rope 17 is wound once around the drum and one end of this rope is attached to a hammock 18 or chair or other appliance 90 adapted to support a person or persons. I prefer employing a hammock, as the same may be provided with a pillow 19 and will, therefore, be especially adapted for lowering injured persons. I prefer a hammock also 95 because it is readily adapted for use as a stretcher, so that it will not be necessary to remove an injured person from the hammock after lowering him. The hammock may, of course, be detachably connected to the lowering 100 rope for this purpose. The other end of the rope 17 extends inwardly toward the building and is passed through a brake or retarding device rigidly supported by horizontal arms 20 projecting inwardly from the 105 supporting shaft or bar 12. This brake consists of a grooved plate 21 having upstand-

ing rigid ears 22 at its opposite edges. In the upper ends of ears 22 is pivoted a lever 23 having an angular arm 24 at its lower end, which is pivotally connected to a pressure plate 25 adapted, when the lever is pressed downwardly, to frictionally depress the rope into the groove in the bottom plate and thus form a friction brake. The lever 23 extends toward the building, so as to be readily accessible by persons at the adjacent window of the building, but it will be understood, of course, that this lever may be controlled by a person standing on the ladder, and it will be understood also that the weight of the lever may be sufficient in some cases to give the degree of braking action necessary. To prevent the lever 23 from being thrown over far enough to carry the pressure plate 25 out of operative position, I attach to this plate 25 a loop 26.

To keep the ladder sections a proper distance from the wall of the building, I provide one or more of the sections 10 with a device such as shown in Figs. 9 and 10. This device consists of a suitable pair of brackets 27 fastened in any suitable manner to the inner face of the ladder and projecting toward the building, their inner ends being connected by horizontal bar 28. I journal at each end of these bars, on a vertical axis, a roller or wheel 29 which is adapted to bear against the building and roll along the face thereof as the ladder is moved back and forth.

I journal in each of the hanger bars 5 a rock shaft 30 whose inner end is bent upwardly to form a hook 31 which extends up behind the rail 1, and whose outer end is provided with a weighted arm 32. The weight normally holds the finger or hook 31 up behind the rail and thereby prevents the hangers from jumping off the track. As the ladder is moved along the rail, the hooks 31 strike against brackets 2 and cause the rock shaft 30 to rotate far enough to permit the hooks 31 to pass by the brackets, and, when the hooks have passed the brackets, the weighted arms will restore them to normal position.

In Fig. 3 I show a platform 33 which may be removably attached to any one of the ladder sections at any point to enable persons to stand thereon when assisting in the rescue of persons from a burning building. This platform is detachably connected to the ladder by any suitable means, but preferably by hooks 34 and a pair of hangers 35 adapted to engage over the rungs of the ladder.

It will be observed that by pulling on the free end of the rope 17, the drum will rotate and the hammock or stretcher will be raised to the desired point. After the person rescued is placed in the hammock, the hammock may be lowered with any de-

sired speed by paying out the rope and applying the proper degree of braking action on the rope by means of lever 23. When the loaded stretcher is thus lowered, the drum does not rotate, being held against rotation by the spring pawls 16, so that the retarding action is greatly increased by compelling the rope to slide frictionally around the drum. I have found in practice that by thus locking the drum against rotation while lowering the load and by employing an additional friction clamp, I may lower the heaviest loads with but very little manually-applied friction.

It will be understood that any suitable form of hinged connection may be used between the ladder sections. In Fig. 11 I show one desirable form consisting of a pair of clips connected by a loose link 10^a whereby the ladder sections may be folded over upon each other flatwise, so as to occupy but a small space for convenience of packing and shipping. In Fig. 12, the ladder sections are shown connected together so as to be separated readily, a hook 10^b being used for this purpose, this connection being especially desirable for the lowest section of the ladder to permit this section to be removed whenever desired.

It will be observed that a feature of importance in my invention lies in the idea of mounting on a depending traveling ladder a drum in such manner that the same may be adjusted up and down on the face of the ladder, so that it may be readily positioned properly for making rescues, the drum supporting frame being provided with arms extending inwardly between the bars of the ladder and being provided with a friction brake, this brake being at the inner ends of the arms so that it may be controlled readily by a person in the building or on the ladder. With an apparatus constructed in this manner, it will be seen that rescues may be made at any point on the face of the building, the adjustment being readily accomplished and the descent of the carrier being readily controlled, as stated, by a person either on the ladder or in the building. It is important also that the carrier shall work up and down the front of the ladder, so that while it is being lowered the person or persons on the carrier may steady the carrier by grasping the ladder as the carrier descends.

Having thus described my invention, what I claim is:

1. In a fire escape, an overhead track, a traveling ladder depending therefrom, a drum shaft and means for suspending it non-rotatively at various points along the face of the ladder, a drum journaled on this shaft, ratchet devices for preventing the drum rotating in one direction, a cable mounted on said drum and having a depend-

- ing end connected to a carrier, a manually-controlled friction device connected to said shaft through which device the other end of the cable runs, for the purposes herein set forth.
2. In a fire escape, an overhead track, a traveling ladder depending therefrom, a drum shaft and means for suspending it non-rotatively at various points along the face of the ladder, a drum journaled on this shaft, ratchet devices for preventing the drum rotating in one direction, a cable mounted on said drum and having a depending end connected to a carrier, a frame attached to said shaft and extending inwardly between the bars of the ladder and carrier, a friction plate at its inner end, a lever-operated brake plate mounted at the inner end of said frame, the other end of said cable being extended inwardly and passed between said plates, for the purposes herein set forth.
3. The combination with a ladder of a raising and lowering appliance consisting of a bar and means for mounting it on the face of the ladder at various points along its length, a drum mounted to rotate on said bar, means being provided for preventing the drum rotating in but one direction, a cable wound on said drum and having a depending end connected to a carrier, and a friction brake device carried by said bar adapted to exert a frictional pressure on the free end of said cable.
4. The combination with a ladder of a raising and lowering appliance consisting of a bar and means for mounting it on the face of the ladder at various points along its length, a drum mounted to rotate on said bar, means being provided for preventing the drum rotating in but one direction, a cable wound on said drum and having a depending end connected to a carrier, and a friction brake device carried by said bar adapted to exert a frictional pressure on the free end of said cable, said frictional device being supported on bracket means extending inwardly between the bars of the ladder and carrying the frictional device at the inner end thereof, said frictional appliance embodying a manually-operable lever for controlling the friction.

In testimony whereof I hereunto affix my signature.

JOSEPH S. KNOWLES.
